UNITED STATES PATENT OFFICE.

GLEN M. DYE, OF MINNEAPOLIS, MINNESOTA, ASSIGNEE TO PHOTOGRAPHIC APPLIANCES CORPORATION, OF MINNEAPOLIS, MINNESOTA, A CORPORATION OF MINNESOTA.

CONVEYER-APRON.

1,384,125.

Specification of Letters Patent. Patented July 12, 1921.

Application filed October 12, 1918. Serial No. 257,850.

To all whom it may concern:

Be it known that I, GLEN M. DYE, a citizen of the United States, residing at Minneapolis, in the county of Hennepin and State of Minnesota, have invented certain new and useful Improvements in Conveyer-Aprons; and I do hereby declare the following to be a full, clear, and exact description of the invention, such as will enable others skilled in the art to which it appertains to make and use the same.

My invention relates to improvements in conveying aprons, and has for its especial object to provide such an apron for use in connection with photographic drying machines of the type disclosed and broadly claimed in my U. S. Letters Patent, 1,277,202, issued to me of date August 27, 1918.

In this type of machine, an endless apron is held by guide rollers under the desired tension and arranged to run over a revolving drum heated to the desired temperature. Certain of these guide rollers hold a section of the apron to afford a moving feed table, on which wet photographs are placed and carried onto the periphery of the drum, the diameter of which is sufficiently large to thoroughly dry the photograph, while making substantially one complete rotation.

Just before the drum has made one complete rotation, the apron is directed therefrom by certain of the guide rollers to allow the dried photographs to be released from between the drum and apron and discharged into a receiving tray provided therefor.

It is highly important that the conveying apron for such a machine has a smooth contacting surface with the drum, and which surface must be without wrinkles, creases or pockets, in order that the photographs may be pressed flat against the drum throughout their entire surfaces. It is also highly important to guide such an apron, so that the same will not drift. The apron must also be made of a material that will evenly absorb moisture from the wet prints placed thereon to facilitate the drying thereof and, in turn, the apron must be of a texture that will freely release the absorbed moisture, in order that the apron may stay in a substantially dry condition.

An apron formed of duck or other similar material has been found best suited for use in connection with photographic drying

machines, but such an apron is not entirely satisfactory, for the reason that, in guiding the same to prevent drifting, the apron is liable to transversely sag and form pockets, creases and wrinkles, and these uneven surfaces in the apron will either spoil or mar the photograph coming in contact therewith.

To overcome this difficulty, which is the subject matter of my present invention, I provide an endless apron of duck or other suitable material, and secure thereto a backing that is relatively stiff transversely of the apron, to permit the same to be guided to overcome drifting, and it is relatively pliable longitudinally of the apron, to permit the apron to freely pass over guide rollers. A backing, well suited for this purpose and least expensive, is commercial woven fiber matting, such as grass matting, of the desired width, laid upon the inner face of the apron, with the woof threads extending transversely thereof and with the warp threads extending longitudinally thereof. The longitudinal edges of the apron are then folded upon the corresponding edges of the matting and the two stitched together.

To the above end, generally stated, the invention consists of the novel devices and combinations of devices hereinafter described and defined in the claims.

In the accompanying drawings, which illustrate the invention, like characters indicate like parts throughout the several views.

Referring to the drawings,
Figure 1 is a perspective view of the improved apron in diagram;

Fig. 2 is a fragmentary plan view of the connected ends of the apron, on an enlarged scale;

Fig. 3 is a bottom plan view of the parts shown in Fig. 2;

Fig. 4 is a transverse section taken on the line 4—4 of Fig. 2; and

Fig. 5 is a longitudinal section taken on the line 5—5 of Fig. 2.

The invention includes an endless conveyor apron, of duck or other suitable material, having a backing 7. As shown, the backing 7 is formed of commercial woven fiber matting laid upon the under face of the apron 6 with the woof threads thereof extending transversely of the apron and with

the warp threads thereof extending longitudinally of the apron, said woof and warp threads being indicated by the numerals 8 and 9, respectively. As is well known, the 5 woof threads of fiber matting are formed of a multiplicity of fibers or blades of grass laid one upon the other to form a relatively heavy twine. This twine or woof thread is sufficiently pliable to permit the warp threads 10 to draw into the same, during the weaving thereof, so that said warp threads do not extend outward thereof, thus leaving the faces of the matting relatively smooth.

By reference to Fig. 3, it will be noted 15 that the apron 6 is somewhat wider than the backing 7 to permit the longitudinal edges thereof to be folded under the corresponding edges of the backing and secured thereto by stitches 10. The apron and back- 20 ing are each formed of a single piece of fabric and the apron is somewhat longer than the backing to enable the ends thereof to be folded under the corresponding ends of the backing and secured thereto by the 25 stitches 10 and a plurality of rows of transverse stitches 11. The backing 7 is further secured to the apron 6 by a plurality of longitudinal rows of stitches 12. The two folded ends of the apron 6 are extended 30 slightly beyond the respective ends of the backing to afford a pair of flaps 13, through which a lacing 14 is passed to connect the two ends of the apron.

From the above description, it is evident 35 that the relatively stiff woof threads permit the apron to be easily guided to prevent drift and, at the same time, transversely hold the apron smooth without sags,

creases or wrinkles, while the relatively pliable warp threads permit the apron to freely 40 pass over guide rollers. It is also evident that the moisture absorbed from the wet prints by the apron will be readily taken up by the fibrous backing and, owing to its relatively coarse and loose texture, will freely 45 give off the absorbed moisture under the action of the air and the heat from the drum during the travel of the apron, thus keeping the same in substantially a dry condition. While the texture of the backing is sufficiently 50 loose to permit the free escape of moisture, it is evenly woven so that there are no openings therein which would cause the prints to dry unevenly, thus making the same defective. In actual usage, the above 55 described invention has proven highly efficient for the purpose had in view.

What I claim is:—

A drying conveyer apron comprising a facing and a backing, said facing being a 60 fabric that will readily absorb moisture, and said backing being made up of vegetable fiber stems laid in close parallel arrangement transversely of the apron so as to stiffen said apron transversely, and warp 65 threads connecting said fiber stems and extended longitudinally of the apron so as to give the apron great flexibility in that direction, the said facing and backing being connected so that they act as a single unit. 70

In testimony whereof I affix my signature in presence of two witnesses.

GLEN M. DYE.
